(57) **CLAIM**

The ornamental design for a bead attachment machine, as shown.

DESCRIPTION

FIG. 1 is a left side view of the bead attachment machine showing my new design;

FIG. 2 is a back view thereof;

FIG. 3 is a front view thereof;

FIG. 4 is a right side view thereof;

FIG. 5 is a top view thereof;

FIG. 6 is a bottom view thereof; and,

FIG. 7 is a back perspective view thereof in an alternate position where the spring is not compressed.

Features in broken lines are not claimed.
